Patented May 27, 1919.

UNITED STATES PATENT OFFICE.

WILLIAM D. MOUNT, OF SALTVILLE, VIRGINIA, ASSIGNOR TO NITROGEN PRODUCTS COMPANY, OF PROVIDENCE, RHODE ISLAND, A CORPORATION OF RHODE ISLAND.

APPARATUS FOR TREATING GASES.

1,304,697.

Specification of Letters Patent. Patented May 27, 1919.

Application filed May 9, 1918. Serial No. 233,410.

To all whom it may concern:

Be it known that I, WILLIAM D. MOUNT, a citizen of the United States, residing at Saltville, in the county of Smyth and State of Virginia, have invented certain new and useful Improvements in Apparatus for Treating Gases, of which the following is a specification.

This invention concerns apparatus for mechanically feeding solid material through which a gas is to be passed, so as to exclude air from said gas, especially while said material is being removed from said apparatus; and in one of its aspects said invention relates to an improved automatically feeding stack or tower for removing from a gas to be treated, a substance, such as moisture, the presence of which in said gas is objectionable for subsequent operations.

It has of course long been known to pass moisture bearing gases through a tower filled with solid hygroscopic material; but when considerable moisture or the like is present, the solid material in the tower frequently soon becomes valueless as a purifying or drying agent; if indeed the tower does not become plugged, or at least tend to obstruct the gaseous current.

The present invention therefore has for one of its objects the provision of means whereby the gaseous current to be treated may be permitted to continuously traverse a tower or the like for the purpose of drying or otherwise treating the gas; the drying material, or the like, being supplied more or less continuously to one end of the apparatus and removed in like fashion from the other, with exclusion of air. This and other objects of the invention will be hereinafter referred to but it may be observed at this point, that to thus handle material suitable for drying nitrogen, for example, in such fashion as to prevent contamination of the gas being treated, with oxygen,—involves certain difficulties which the novel combinations of elements and parts now to be described, overcome.

In the accompanying drawing I have illustrated a preferred embodiment of my invention, but as I am aware of various

changes and modifications which may be made therein without departing from the spirit of my invention, I desire to be limited only by the scope of the appended claims, wherein are more particularly pointed out the said combinations.

Referring to the drawing, wherein like reference characters designate like parts in the respective views:

Figure 1 is a front elevation of my improved tower, partly broken away to better show certain of the features thereof;

Fig. 2 is a bottom view of the apparatus;

Fig. 3 is a fragmentary section taken on the line III—III of Fig. 1; and

Fig. 4 is a detail section taken on the line IV—IV of Fig. 3.

The tower preferably comprises a tapering shell or casing 1, the sections of which may be flanged and suitably fastened together as at 2. At the top is a hopper 3 through which, lime, soda-lime, or other material to be used, for example, as a drying and purifying agent, may be introduced; the hopper delivering to a charging valve 4, which, as shown, preferably has a relatively large pocket 4' therein.

When this valve is rotated through substantially 180° the pocket is of course emptied into the tower proper, and neither at such or any other time can the gas being treated, escape, except for such a small quantity thereof as may find its way into and subsequently out of said pocket, as the latter is rotated back to its charge receiving position, or for sweeping out purposes as hereinafter described.

At the bottom of the tower is a rotary table 5 mounted on a spindle 6, which may be integral therewith, and which is preferably continuously driven by suitable gearing.

In the preferred construction a worm gear 7 is secured to the lower end of spindle 6 to drive the latter; the gear 7 being in mesh with a worm 8, the shaft 9 of which carries a beveled pinion 10 which meshes with a bevel gear 11 on the end of the trunnion 12 of a pocketed valve 13, hereinafter referred to. The opposite trunnion 14 of

said valve carries a gear 15, driven in any suitable manner as by the pinion 16.

The table 5 is housed in a casing 17 which supports the tower; being itself in turn supported by its lugs 17'.

A bottom plate 18 closes the casing and provides the bottom of a channel or trough 19 through which is swept the material being removed from the tower. Bottom plate 18 is provided with an annular flange 21 of the table 5 to prevent centripetal movement of said material.

The table also carries sweeps 22 which travel round the channel 19 and collect into batches and push along or propel the material which falls into said channel around to the opening 23 which admits said material to a small hopper 24 leading to the valve 13 aforesaid.

20 This valve is substantially like the charging valve 4, but is preferably smaller, and whereas the valve 4 may be conveniently operated by hand,—valve 13 is preferably continuously power driven; its rate of rotation 25 desirably being such, compared to the speed of rotation of the table 5, as to provide that the pocket 13' therein shall not normally be completely filled at any time before it rotates sufficiently to cut off the flow of material 30 thereinto.

After that the hopper 24 gradually accumulates the bulk of the next charge for valve 13 while the latter is discharging its previous load and its pocket is thereafter being rotated on around to its charge receiving position.

The loads of material falling from valve 13 pass through the conduit 25, or an extension thereof, to their place of deposit.

40 The bottom plate 18 is provided with a bearing 26 for the spindle 6, and is preferably strengthened by ribs 27; while the hopper 24 is attached to the under side of said bottom plate.

45 The table housing 17 has threaded into an opening 28 therein, a pipe 29, through which the gas to be purified enters; an exit pipe 30 for said gas being provided at the upper end of the tower. The housing 17 is so shaped 50 as to provide a preferably circular gas channel above the channel or trough 19 and around the base of the column of solid material, so that gas entering by pipe 29 flows uniformly through the drier charge from this

55 circular channel, and does not tend to rush up the side nearest the inlet, which is so positioned as not to be clogged by the drying material.

In cases where especial care is to be exercised to prevent ingress of even traces of air to the gas being purified, the construction shown in Fig. 3 (and fragmentarily in Fig. 1) may be used. In this case the trunnions of the valve 4 are provided with conduits 31,

32; the former being in the trunnion 33 and 65 the latter in trunnion 34. These trunnions are preferably journaled in bushings 35 disposed in the heads 36—36' upon the respective sides of the valve casing. These heads permit the introduction of the valve into said 70 casing and serve as lateral guides or retainers.

To the head 36' is bolted a cap 37, which is preferably taper-bored to receive the similarly tapered end of the corresponding valve 75 trunnion 34; the packing 38 permitting of a nice adjustment of the cap with respect to the trunnion-end, to afford a running fit which is gas-tight.

A somewhat similar, but centrally apertured, cap 39 engages a tapered part of the trunnion 33 in like fashion; and an extension 33' of said trunnion carries a handle 40, by which the valve may be rotated, preferably in the direction of the arrow, in Fig. 1. 80 85

As shown in Figs. 3 and 4, a port 41 extends through the wall of trunnion 33, from conduit 31, so that while normally there is no communication between the latter and a vent 42' leading to the outer air, or wherever 90 desired,—when the valve, after receiving its charge, has been rotated, as indicated, through about 90°, a regulated flow of the gas being treated in the tower, *e. g.* nitrogen, will pass up the pipe 42 (if valve 43 be 95 opened or partly opened), and traverse a similar port 41' in trunnion 34, to then pass in succession through conduit 32, the interstices in the charge in the valve, conduit 33 and the said port 41, to the outer air or elsewhere through the vent 42'.

In this way the air in the interstices of the load or charge in the valve may be swept out, especially if the valve 4 be held in the described position for an instant or two. 105

As this valve is further rotated toward its load discharging position, the ports will close to prevent further escape of the pure gas and will only be opened again when the above described operation is to be repeated, 110 following the introduction of a further load into the charging valve. The crank 40 is, of course, preferably turned always in one direction.

I have discovered that it is desirable to 115 provide positively acting means to regulate the speed of delivery of the spent solid material from the tower, and to this end I preferably provide a circular apron 44 of light sheet metal, adapted to slide up and down 120 within a downward extension or flange 44', in the housing 17.

This apron is supported by angle clips 45, or the like, attached to threaded rods 46 which may project through the housing and which may be provided with helical springs 46' thereon, to readily permit of vertical adjustment of the apron. 125

The operation of the apparatus, as a whole, when used to dry nitrogen or the like, is as follows:

The tower is charged with lime or soda-lime through the charging valve 4,—preferably with the valve 43 adjusted to an open or partly open position, to free the incoming material of air, as just described,—and as the contents of the tower are gradually withdrawn from below, fresh material is incrementally introduced to keep the apparatus properly charged.

With the table rotating at any definite speed and drying material, or the like, of a certain fineness being fed through the drier, the rate of feeding can be increased by raising the apron, or decreased, if desired, by lowering it.

In adapting the apparatus for use with different drying materials, it would be necessary to properly proportion the diameter of the table, and, in a general way, its speed of revolution, to the diameter and distance from the table of the lower edge or bottom, of the flange 44', or the equivalent of the latter. Having made this rough adjustment, the apron provides the finer, flexible adjustment needed. The proper position of the apron for the desired rate of feed will then be dependent upon the angle of the material being rotarily fed, as determined by the physical characteristics of said material.

The nitrogen to be treated passes into the casing 17 through pipe 29 and thence traverses the interstices between the lumps or particles of the drying medium, to finally escape from the tower via pipe 30.

The greater part of any moisture present in the gas is of course removed by the lime or the like in the casing 17 and in the lower section of the tower, and as this absorbent material is thereby gradually hydrated until it becomes substantially valueless as a drying agent, it is removed from the tower by the rotation of the table 5 which works the material upon its surface out toward its periphery until said material drops into the channel 19, from which it is removed by the sweeps 22 into the hopper 24, whence, as the valve 13 automatically turns to receive it, it drops into the pocket 13' to be subsequently delivered thence through conduit 25.

Obviously, even though said conduit should deliver directly to the outer air, little if any of the latter can find its way into the tower; but to preclude even the entrance of the small quantities of air trapped in the pocket of valve 13, when its pocket orifice is ascending, I prefer to deliver the spent charge to an air-tight receptacle 47; which, if desired, may be initially filled with pure nitrogen.

Thus admission of air to the tower by reason of the removal of the drying mate-

rial, or the like, is substantially prevented 65 and the charging valve 4, at the top, similarly excludes air at this point.

Finally, it may be well to point out the value of the provision of downwardly and outwardly spreading or tapering the walls 70 of the tower, especially when the apparatus is embodied in a lime drier or the like. Where it is attempted to thus more or less continuously feed lime or other moisture absorbing material through a tower of considerable height, e. g. ten feet, by gravity in co-action with a feed table such as that described,—it will be found that if the tower is not shaped like, for example, a truncated cone, but rather is cylindrical, the material 80 descending through the tower will frequently choke or clog, as it expands considerably during its absorption of moisture; in which case the device soon becomes inoperative both as a feeding mechanism and 85 as regards its function as a means for removing moisture or the like from the gas passed therethrough.

Having thus described my invention, what I claim is:

1. In gas-treating apparatus, the combination of a substantially vertical stack through which a substantially unbroken column of gas-treating material is fed by gravity, with means to introduce said material in solid form but in pieces at the upper part of said stack while substantially excluding air, a rotating feed table to directly support substantially the entire bulk of the material in said stack, means to rotate said table to feed said material gradually off from the table surface, means to receive the so removed material and deliver it from said apparatus while preventing air from flowing therethrough up into the gas 100 being treated, means to conduct the gas to be treated to one part of said column of material for continuous and substantially uninterrupted upward passage through the interstices of said bulk of material and means 110 to conduct the treated gas away from the upper part of said column.

2. In gas-treating apparatus, the combination of a substantially vertical stack through which a column of gas-treating 115 material is fed by gravity, with means to introduce pieces of said material at the upper end of said stack while substantially excluding air, a rotating feed table to support the material in said stack, a trough around 120 said feed table, means to rotate said table to feed said material gradually off from the table surface into said trough, sweeping means, attached to and movable with said table, to propel the so removed material 125 along said trough, means to receive said material from said sweeping means and deliver it from said apparatus while prevent-

ing air from flowing therethrough up into the gas being treated, means to conduct the gas to be treated to one part of said column of material for passage upwardly through 5 the interstices of said material, and means to conduct the treated gas away from an upper part of said column.

3. In gas-treating apparatus, the combination of a substantially vertical stack 10 through which a substantially unbroken column of gas-treating material is fed by gravity, with means to introduce fresh material to said stack while substantially preventing an inflow of air into the gas being treated, 15 means to remove from the apparatus the treating material which has been impaired during its passage through said stack, said removing means including a power-driven rotating table which directly supports said 20 column and feeds the impaired material away from the base of said column, means to collect into batches and propel along the impaired material delivered by said table, and a power driven device for delivering said 25 impaired material to a point outside of said apparatus while substantially excluding an inflow of air.

4. In gas-treating apparatus, the combination of a substantially vertical stack through 30 which a column of gas-treating material is fed by gravity, with means to introduce fresh material to said stack while substantially preventing an inflow of air into the gas being treated, means to remove from the 35 apparatus the treating material which has been impaired during its passage through said stack, said removing means including a power-driven rotating table which supports said column and feeds the impaired 40 material away from the base of said column, means to collect the impaired material delivered by said table, a power driven device for delivering said impaired material to a point outside of said apparatus while sub- 45 stantially excluding an inflow of air and connections between said table and device to maintain a determined relationship between the speeds of movement thereof.

5. In gas-treating apparatus, the combination of a substantially vertical stack through 50 which a column of gas-treating material is fed by gravity, with means to introduce fresh material to said stack while substantially preventing an inflow of air into the 55 gas being treated, means to remove from the apparatus the treating material which has been impaired during its passage through said stack, said removing means including a power-driven rotating table which supports 60 said column and feeds the impaired material away from the base of said column, means to collect the impaired material delivered by said table, a rotary pocketed valve through which incrementally passes said impaired

material, and means to drive said table and valve at speeds which bear a predetermined relationship to each other.

6. In apparatus for purifying nitrogen gas or the like, a stack to contain solid material through which is passed the gas to be purified, means to supply a current of the gas to be treated, to said material at the bottom thereof, means to gradually remove parts of said material from the lower end of said stack as the purifying properties of said parts become impaired, means to charge the upper part of said stack with fresh material, to replace that removed, and means to conduct the purified gas away from the upper end of said stack, said charging means including provisions for sweeping out air present in the solid material being introduced, before said material is delivered to said stack. 80

7. In apparatus of the class described, the combination of a principal receptacle for holding a charge of fragmentary material to be subjected to the action of a gas, with a secondary receptacle for at times temporarily holding a quantity of said material apart from said charge, one of said receptacles being disposed with respect to the other to permit of movement of a given quantity of said material from one of said receptacles into the other when said receptacles are in communication with each other, means for establishing and disestablishing said communication, and means for forcibly displacing any air present in said secondary receptacle prior to the establishment of communication between said receptacles in manner aforesaid, said air displacing means including a conduit through which is supplied a gas which is innocuous to the operation to be effected in said principal receptacle and means to control the flow of said innocuous gas through said secondary receptacle, whereby the air may be swept out of said secondary receptacle by said flow of innocuous gas. 95

8. In apparatus of the class described, the combination of a principal receptacle for holding a charge of fragmentary material to be subjected to the action of a gas, with a secondary receptacle for at times temporarily holding a quantity of said material apart from said charge, one of said receptacles being disposed with respect to the other to permit of movement of a given quantity of said material from one of said receptacles into the other when said receptacles are in communication with each other, means for establishing and disestablishing said communication, means for forcibly displacing any air present in said secondary receptacle prior to the establishment of communication between said receptacles in manner aforesaid, said air displacing means including a

conduit through which is supplied a gas which is innocuous to the operation to be effected in said principal receptacle and means to control the flow of said innocuous 5 gas through said secondary receptacle, whereby the air may be swept out of said secondary receptacle by said flow of innocuous gas, and operative connections between said communication establishing means and said air displacing means for conserving said 10 flow of gas.

In testimony whereof I have affixed my signature, in the presence of two witnesses.

WILLIAM D. MOUNT.
